FOLDING CHAIR WITH INDEPENDENT AND AUTOMATIC SEAT FOLD

Gerald V. Spencer, Grand Rapids, Mich., assignor to American Seating Company, Grand Rapids, Mich., a corporation of New Jersey

Application May 16, 1956, Serial No. 585,241

3 Claims. (Cl. 155—142)

The present invention relates to folding chairs and more particularly to steel folding chairs of the inverted Y-type.

The primary objects of the invention are to provide a folding chair of the type indicated in which, when the chair is unfolded for use, the seat may be lowered to a use position for occupancy or raised to a non-use position permitting the chair occupant to rise and stand rearwardly to facilitate ingress and egress of other persons passing in front of him between rows of such chairs; to provide such a folding chair having an operating rod which may be lifted for folding the chair into a compact unit for storage with the rear legs thereof lying alongside the front legs and with the seat positioned between the front legs, and which operating rod can be lowered to unfold the chair for use; to provide such a folding chair in which, when the chair is unoccupied, the seat automatically assumes a position intermediate its fully lowered position for occupancy and its fully raised position, and in which all of the seats in a row of such chairs automatically assume the same angle of tilt when unoccupied; to provide such a chair which is so constructed that two or more chairs can be connected in side-by-side relation and the operating rods thereof easily interconnected so that the connected chairs can all be folded simultaneously, and with the interconnecting means for the operating rods serving as a handle or handles by means of which the folded section of chairs can be carried; and in general to provide such a folding chair which is sturdy in construction, efficient in use, and reasonably economical in manufacture.

An illustrative embodiment of the invention is shown in the accompanying drawing, wherein:

Figure 1 is a view of the new folding chair shown partly in side elevation and partly in vertical section taken on line 1—1 of Figure 4, the chair being here shown unfolded for use and the seat thereof being indicated in its normal unoccupied position in full lines, in its lowered position of use in dotted lines and in its fully raised non-use position in broken lines;

Figure 2 is a side elevational view of the chair in partially folded condition;

Figure 3 is a side elevational view of the chair in fully folded condition for storage;

Figure 4 is a fragmentary front elevational view of a pair of the chairs secured together in side-by-side relation to form a 2-chair section;

Figure 5 is an enlarged fragmentary vertical sectional view of certain parts of the chair taken on line 5—5 of Figure 4; and

Figure 6 is an enlarged fragmentary sectional view of certain parts of adjoining connected chairs taken on line 6—6 of Figure 4, the plane of section being also indicated by line 6—6 of Figure 2.

Referring now in detail to this drawing wherein like parts are designated by the same numerals in the several views, the chair there shown generally comprises an inverted U-shaped tubular metal front frame forming a

10 connected by a bight portion 11 in which is secured a back support panel 12, a pair of forwardly-upwardly extending tubular metal rear legs 13 having their upper ends hingedly connected at 14 to the front legs 10, and a seat 15 pivotally mounted between the front legs 10 for swinging movement between a fully lowered use position indicated in dotted lines in Figure 1 and a fully raised non-use position indicated by broken lines in Figure 1. The seat is pivotally mounted for such swinging movement on an upper front tie-rod 16 which connects the front legs 10 at the approximate seat level of the chair.

A lower front tie-rod 17 also connects the front legs 10 of the chair below the seat level thereof, and the chair is strengthened by an inverted U-shaped strut 18 of rod stock which has its lower ends secured to the front legs 10 and its upper middle portion secured as by welding to the lower tie-rod 17.

An upper rear tie-rod 19 connects the chair's rear legs 13 at the approximate seat level thereof, and a lower tie-rod or strut 20 connects the rear legs 13 near their lower ends for additionally strengthening the chair. Seat stiles 21 secured to opposite sides of the seat 15 as by means of rivets 22, extend rearwardly of the seat and are provided on their upper sides with stops 23 of rawhide or the like adapted to contact the underside of the upper rear tie-rod 19 to silently stop the lowering movement of the seat when it reaches its lowered use position.

A bracket 24 is secured as by welding to the underside of the seat 15 at one side thereof, said bracket 24 having a depending arm 25. A helical spring 26 has its upper end connected to this depending arm 25 and has its lower end connected to the lower front tie-rod 17. Spring 26 normally maintains the seat 15 at its angle of tilt shown in solid lines in Figures 1 and 5, which position of the seat facilitates ingress and egress of persons between rows of unoccupied chairs. From this normal position of the seat, it can be lowered to its use position indicated in dotted lines by the weight of an occupant, or elevated to its fully raised non-use position indicated in broken lines when the occupant rises and stands rearwardly to permit others to pass in front of him.

A pair of arms 27 are pivotally connected as by means of rivets or pins 28 to the rear legs 13 and extend forwardly therefrom over the upper front tie-rod 16 and thence forwardly-downwardly and terminating at points beneath the seat 15 when the seat is in its lowered position. A pair of links 29 have their forward ends pivotally connected to the upper front tie-rod 16 and have their rearward ends pivotally connected at 30 to the adjacent arms 27 at points thereon between the adjacent front and rear legs.

An operating rod 31 connects the forward ends of arms 27 beneath the seat 15. It will readily be seen that when the various parts of the chair are in their unfolded use positions seen in full lines in Figure 1, lifting movement of the operating rod 31 transmitted through arms 27 and links 29 will swing the rear legs 13 to folded positions alongside the front legs 10. During the latter part of this lifting movement of the operating rod 31 it directly contacts the underside of seat 15, moving the seat to its fully folded position between the front legs of the chair. The chair is shown partly folded in Figure 2 and fully folded in Figure 3. When the operating rod 31 is lowered to again unfold the chair, the front legs and rear legs are spread apart and the seat is again permitted to occupy its position shown in full lines in Figure 1.

Figures 1, 4 and 6 illustrate the manner in which two identical chairs can be secured together in side-by-side relation. Upper front clamps 32 and lower front clamps 33 secure the adjacent front legs 10 of adjoining chairs together, and rear clamps 34 connect the adjacent rear legs 13 of the adjoining chairs. Prior to applying these

3
clamps, a connecting pin 35 has its reduced opposite end portions 36 fitted into sockets 37 extending through arms 27 and into the operating rods 31 of the adjoining chairs, the operating rods being desirably tubular to this end. By this means the two chairs may be folded simultaneously by lifting the connecting pin 35 and, after folding, the connecting pin 35 serves as a handle by means of which the connected chairs can be carried.

It will thus be seen that the invention provides an efficient folding chair in which the seat is independently 10 movable between a lowered use position and a raised non-use position and in which the seat, when unoccupied, automatically assumes a tilted position intermediate its raised and lowered positions, and that the invention provides quickly attachable and detachable means for coupling together two or more chairs to form a section of chairs.

While but one specific embodiment of the invention has been herein shown and described, it will be understood that numerous details may be altered or omitted without departing from the spirit of the invention as the same is defined by the following claims.

I claim:

1. In a folding chair: a pair of spaced front legs; a pair of spaced rear legs having their upper ends hingedly connected to the front legs; a seat pivotally mounted between the front legs for swinging movement between a lowered position of use and a raised position of non-use; a pair of arms pivotally connected to the rear legs and extending forwardly beyond the seat's pivotal connections with the front legs and terminating at points beneath the seat in the latter's lowered position; a pair of links having their forward ends pivotally connected to the front legs and their rearward ends pivotally connected to said arms at points between the adjacent front and rear legs; and an operating rod connecting the forward ends of said arms, whereby lifting movement of the operating rod swings the rear legs to folded positions alongside the front legs and swings the seat upwardly to a folded non-use position, and whereby lowering movement of the operating rod unfolds the chair legs and permits swinging movement of the seat between its raised non-use position and its lowered use position.

2. A pair of folding chairs according to claim 1 secured together in side-by-side relation characterized by having 45 sockets extending through the arms and into the operating

5 rods, and a handle having its opposite ends fitted into the adjacent sockets of the two chairs whereby the chairs may be folded and unfolded simultaneously and by means of which handle the connected chairs may be carried when folded.

3. In a folding chair: a pair of spaced front legs; a pair of spaced rear legs having their upper ends hingedly connected to the front legs; a front tie-rod connecting the front legs and a rear tie-rod connecting the rear legs, both of said tie-rods being located at the approximate seat level of the chair; a seat pivotally mounted on the front tie-rod for swinging movement between a lowered position of use and a raised position of non-use; stops on the rear of the seat adapted to contact the rear tie-rod to limit the lowering movement of the seat to its position of use; a pair of arms pivotally connected to the rear legs and extending forwardly therefrom over the front tie-rod and thence forwardly-downwardly and terminating at points beneath the seat in the latter's lowered position; a pair of links having their forward ends pivotally connected to the front tie-rod and their rearward ends pivotally connected to said arms at points between the adjacent front and rear legs; and an operating rod connecting the forward ends of said arms, whereby lifting movement of the operating rod 25 swings the rear legs to folded positions alongside the front legs and swings the seat upwardly to a folded non-use position, and whereby lowering movement of the operating rod unfolds the chair legs and permits swinging movement of the seat between its raised non-use position and its lowered use position; a second front tie-rod connecting the front legs below the seat level; and a spring connected to said second front tie-rod and to the seat at a point below the first front tie-rod on which the seat is pivoted, whereby the seat is normally biased toward a position 30 intermediate its raised and lowered positions.
